UNITED STATES PATENT OFFICE

JESSE G. KING AND OTTO M. SUMMERS, OF DAYTON, OHIO, ASSIGNEES, BY MESNE ASSIGNMENTS, TO FRIGIDAIRE CORPORATION, A CORPORATION OF DELAWARE

REFRIGERATING APPARATUS

Application filed July 21, 1928. Serial No. 123,892.

The present invention relates to refrigerating systems, and particularly to refrigerating systems having relatively high and low pressure portions.

One of the objects of the present invention is to insure the safety of refrigerating systems by providing for the escape of refrigerant from the high-pressure portion to the low-pressure portion, in case of excessive pressure in the high-pressure portion, while providing for the operation of the system to procure refrigeration after the excessive pressure has been relieved and thereafter give warning that the system has operated abnormally.

Another object of the present invention is to provide an excessive pressure safety valve which, after once functioning to relieve excessive pressure, will permit a restricted amount of fluid to escape.

A still further object is to provide a safety valve which is reliable and which can be manufactured at a relatively low cost.

Further objects and advantages of the present invention will be apparent from the following description, reference being had to the accompanying drawings, wherein a preferred form of the present invention is clearly shown.

In the drawings:

Fig. 1 is a diagrammatic view of one form of the improved refrigerating system;

Fig. 2 is a longitudinal cross-sectional view of the improved valve used in the system;

Fig. 3 is a fragmentary sectional view of a needle of the valve;

Fig. 4 is a plan view of the needle looking from the bottom;

Fig. 5 is a fragmentary sectional view of the valve showing the position thereof when excessive pressure is present within the system; and

Fig. 6 is a plan view of a punctured disc of the valve.

Referring to the drawings, there is shown an evaporator or cooling unit 20 provided with an outlet conduit 21 and an inlet conduit 22. Refrigerant is withdrawn from the evaporator 20 through the conduit 21 by a

compressor 23. The compressed refrigerant is delivered from the compressor 23 to a condenser 24 through a pipe 25. The condensed refrigerant passes from the condenser 24 to the evaporator 20 through the pipe 22.

The compressor 23 is driven by a motor 27 and is controlled by a switch 28 having an expandable chamber 29 which is connected with the pipe 21 by pipe 30 and is, therefore, responsive to the pressure within the low-pressure side of the refrigerating system. When the pressure within the low-pressure side attains a certain high value, the switch will operate to complete an electrical circuit to the motor and when the pressure within the low-pressure side attains a certain low value the switch will operate to interrupt the electrical circuit.

The condenser includes a refrigerant-receiving tank 32 in which there is located a water coil 33 which is utilized for cooling the refrigerant received by the tank 32. The condenser 24 which is located on the relatively high-pressure side of the refrigerating system, is connected by a by-pass to the low-pressure side of the refrigerating system. This by-pass includes a conduit 34 and an excessive, high-pressure, relief valve 35, which valve controls the flow of refrigerant from the high-pressure side to the low pressure side. The flow of water through the coil 33 can be controlled in any well-known manner, as, for example, by a valve 33^a which is responsive to the pressure within said tank.

Valve 35 includes a hollow body 36 having a nipple 37 at one end thereof for connection with the conduit 34 and is provided with a nipple 38 by which it is secured with a coupling 39. Coupling 39 includes a member 40 having a nipple 41 which is connected with the condenser tank 32 and is provided with a shoulder 42. Coupling 39 also includes a nut 44 adapted to screw-threadedly receive the nipple 38, and is provided with a shoulder 45 which is arranged to engage the shoulder 42 of member 40. A disc 46 rests upon the end of the member 40 and is clamped between said member and the end of nipple 38.

Body 36 is provided with a chamber 48 in which is located a sleeve 49 having a flange 50 which rests upon the disc 46. A pin 51 is located within the sleeve 49 and terminates 5 directly above the disc 46. Pin 51 is carried by a member 52 having a flange 53. A spring 54 is interposed between the flange 53 and flange 50 and normally tends to maintain the sleeve in engagement with the disc 10 46. A passage 55 in nipple 36 is connected with the chamber 48 through a slot 56 formed within the upper portion of flange 53. A passage 58 extends through member 40 and is in direct alignment with the needle 15 51.

The disc 46 is constructed of puncturable or fracturable material, such as solder, German silver, or the like. When excessive pressure is present within the high-pressure side 20 of the refrigerating system, such pressure acting upon the bottom of the disc 46 will force the same upwardly by moving sleeve 49 upwardly against the tension of spring 54. Since the pin 51 is stationary, the upwardly-moving disc 46 will engage same and will be punctured thereby, as shown in Fig. 5. Thus the excessive pressure will be relieved, since the pressure from the high-pressure side will pass the puncture within 30 the disc and enter chamber 48, whence it passes to the low-pressure side through passages 56 and 55, and conduit 34.

The bottom portion of pin 51 is inclined, as at 60, and is concaved at a greater angle, 35 as shown at 61, so as to provide a substantially V-shaped cutting surface. Therefore, when the disc 46 is punctured, the puncture is in the shape of a V, as shown in Fig. 6. When the pressure within the high-pressure 40 side recedes, spring 54 will force the sleeve, and likewise the disc 46, downwardly while the normal pressure within the high-pressure side will maintain the V-shaped puncture substantially in alignment with the remaining portion of the disc. Therefore, when the pressure within the high-pressure side 45 recedes, the puncture is substantially closed, but will permit a restricted amount of fluid to escape therethrough. The restriction is such as to limit the flow from the high-pressure side to the low-pressure side to such a degree that the compressor will still withdraw sufficient refrigerant from the evaporator 20 that refrigeration will take place 50 within said evaporator. However, the flow through the puncture will permit enough refrigerant to pass therethrough so that the compressor will operate continuously or substantially continuously.

60 Thus, a refrigerating system has been provided in which the safeness thereof has been enhanced and which also gives warning, after there was an occurrence of a temporary abnormal function, that the system has not 65 functioned properly; while, at the same time,

refrigeration continues after the temporary abnormal condition has subsided. If the refrigerating system temporarily does not function normally, due to, for example, temporary clogging of the water-cooling coil, or a temporary non-performance of a control valve for said coil, an excessive pressure will be created and the valve 35 will function. When the abnormal condition has corrected itself to such a degree that the pressure in the system is substantially normal, refrigeration will continue. However, there may be a condition which should be corrected, for example, the repairing of the water coil or readjustment of the control valve thereof. 70 Therefore, although refrigeration still continues, the compressor will operate substantially continuously, thus giving a readily-noticeable warning that the system has at one time not functioned properly and that 75 corrections should be made.

While the form of embodiment of the invention as herein disclosed, constitutes a preferred form, it is to be understood that other forms might be adopted, all coming 80 within the scope of the claims which follow.

What is claimed is as follows:

1. A refrigerating system having a relatively high-pressure side and a relatively low-pressure side including a cooling unit, a compressor for circulating a refrigerating medium, and conduits connecting said compressor and unit; of a by-pass between said high and low sides; and means for opening said by-pass to relieve excessive pressure in the high side, said means being constructed and arranged to close partially after the excessive high pressure is relieved to provide for the flow of a restricted quantity of medium through said by-pass. 95

2. A refrigerating system having a relatively high-pressure side and a relatively low-pressure side including a cooling unit, a compressor for circulating a refrigerating medium, and conduits connecting said compressor and unit; of a by-pass between said high and low sides; and a valve in said by-pass having a fracturable element adapted to be fractured due to excessive pressure on said high side and adapted to be closed partially by the pressure in said system after the excessive pressure is relieved to provide for the flow of a restricted quantity of medium through said by-pass. 110

3. A refrigerating system having a relatively high-pressure side and a relatively low-pressure side including a cooling unit, a compressor for circulating a refrigerating medium, and conduits connecting said compressor and unit; of a by-pass between said high and low sides; and a valve in said by-pass having a disc adapted to be punctured due to excessive pressure on said high side and adapted to be closed partially by the pressure in said system after the excessive 120 125 130

pressure is relieved to provide for the flow of a restricted quantity of medium through said by-pass.

4. A pressure relief valve comprising a valve body, a fracturable disc member, a pin member adapted to fracture said disc, the cutting surface of said pin member being concaved and disposed at an oblique angle with respect to said disc, one of said members being responsive to pressure within said body and movable with respect to the other.

5. A pressure relief valve comprising a casing having an inlet and an outlet, a flexible diaphragm, a spring coil pressing said diaphragm, and a diaphragm puncturing device within said coil.

6. A pressure relief valve comprising a valve body, a puncturable member, a movable sleeve member bearing against said puncturable member and a stationary member located within said sleeve member adapted to puncture said puncturable member.

7. A pressure relief valve comprising a valve body, a puncturable member, a movable sleeve member bearing against said puncturable member, a flange on said sleeve, a spring bearing against said flange and maintaining said sleeve in contact with said puncturable member and a stationary member located within said sleeve member and adapted to puncture said puncturable member.

35 In testimony whereof we hereto affix our signatures.

JESSE G. KING.
OTTO M. SUMMERS.
